CLAIM

The ornamental design for a fan blade cage, as shown and described.

DESCRIPTION

FIG. 1 is a perspective view of the fan blade cage.

FIG. 2 is a front view of the fan blade cage.

FIG. 3 is a side view of the fan blade cage, the opposite side being a mirror image of that shown.

FIG. 4 is a rear view of the fan blade cage.

FIG. 5 is a side view of the fan blade cage.

FIG. 6 is an top plan view of the fan blade cage.

FIG. 7 is a bottom view of the fan blade cage.

FIG. 8 is a cross-section view of the fan blade cage.

FIG. 9 is a perspective view of an alternative embodiment of the fan blade cage; and,

FIG. 10 is a cross-section view of the alternative embodiment of the fan blade cage shown in FIG. 9.

The broken line showing of environmental structure in FIGS. 1-10 is for illustrative purposes only and forms no part of the claimed design.
